CLAIM

The ornamental design for a three-legged cube connector for
wall panel system, as shown and described.

DESCRIPTION

FIG. 1 is a first perspective view of a three-legged cube
connector for wall panel system showing our new design;
FIG. 2 is a second perspective view thereof;
FIG. 3 is a front elevation view thereof;
FIG. 4 is a rear elevation view thereof;
FIG. 5 is a top plan view thereof;
FIG. 6 is a bottom plan view thereof.
FIG. 7 is a left side elevation view thereof; and,
FIG. 8 is a right side elevation view thereof.
